(57) **CLAIM**

The ornamental design for a D-shaped handle tray, as shown and described.

DESCRIPTION

FIG. 1 is a front perspective view of one embodiment of the design;

FIG. 2 is a left side view thereof;

FIG. 3 is a front view thereof;

FIG. 4 is a right side view thereof;

FIG. 5 is a top view thereof;

FIG. 6 is a rear view thereof;

FIG. 7 is a bottom view thereof;

FIG. 8 is a perspective view of a second embodiment of the design, the only difference being the additional inner surface of the tray; and,

FIG. 9 is a perspective view of a third embodiment of the design, the only differences being the additional surfaces of the tray and the different hole in the tray for receiving an alternate type of handle, shown in dotted lines.

Elements shown in dotted lines are not part of the claimed design.
